UNITED STATES PATENT OFFICE

HERMAN P. CLAUBERG, OF JERSEY CITY, NEW JERSEY, ASSIGNOR TO R. HOE & CO., INC., OF NEW YORK, N. Y., A CORPORATION OF NEW YORK

CHUCK MECHANISM FOR WEB ROLLS

Application filed October 22, 1926. Serial No. 143,343

This invention relates to certain improvements in chucks or journals for supporting the web rolls in printing machines.

A particular object of the present invention is to provide a chuck of improved construction provided with a supporting part or member which can be moved into and out of operative relation with the spindle of a web roll, and which can be locked in operative position so as to prevent the accidental displacement of the roll when unwinding.

A further object of the invention is to produce a chuck of few parts and of simple arrangement which can be readily and quickly moved into and out of operative relation with the web roll, and in which a simple means is provided for effecting an adjustment of the parts.

With these and other objects not specifically referred to in view, the invention consists in certain novel parts, arrangements and combinations which will be described in connection with the accompanying drawings and the novel features pointed out in the claims hereunto appended.

In these drawings,—

Figure 1 is a side view, partly broken away and partly in section, of the improved chucks, the parts being shown in roll holding position;

Figure 2 is a partly broken away end view of one of the chucks shown in Fig. 1, the view being taken looking in the direction of arrow 2 of that figure, and

Figure 3 is a sectional view taken on the line 3—3 of Fig. 2, showing the adjusting devices and the parts in position when moved clear of a roll.

Referring now to these drawings, there is shown a web roll R, which is provided with the usual core 1 shown in dotted lines, the core being an iron pipe or the like, on which the roll is wound. This roll is supported at each end by one of the improved chucks. These chucks are duplicates of each other, one being provided for each end of the rolls. While the specific construction of these chucks may be somewhat varied, they will include a part which may be moved to enter the roll spindle and form a bearing for the roll so that the

roll may freely rotate in the machine, and the chuck will include a means for locking the movable part in its adjusted position in the roll core.

In the particular construction illustrated, the chuck is supported in suitable framing 2 and will include a two part block 3, 3', which has a sliding movement, as a whole, in a recess 4 in the frame 2, the two parts of the block also having a relative sliding movement, hereinafter referred to. The block 3' carries at its front end a journal for the roll which consists of a cone-shaped member 5 which is secured to a projection 6 formed on the end of the block by a collar 7 and a screw 8. The cone-bearing 5 fits over a sleeve 9 which has ball-bearing engagement in a recess 10 formed in the face of the block, and is also provided with roller-bearing engagement between the sleeve and the projection 6 on the block, before referred to. Thus the bearing 5 has a very free rotation in the block.

Means are provided for effecting a longitudinal movement of this block to operatively position the cone-bearing in the core of the roll. While these means may be somewhat varied, as shown, the block 3 is provided on one face with a rack 12 with which engages a pinion 13 carried on a rock shaft 14 supported in the framing. This rock shaft at its outer end has secured thereto a hub 15 to which is secured an operating arm 16 provided with a handle 17 by which the arm may be rotated. It will be seen by the rotation of the handle 17 the rack will be operated to move the cone-bearing from the position shown in Fig. 3, where it is clear of the roll core, to that shown in Fig. 1, where it engages the core.

In the best constructions, means are provided for locking the parts in adjusted position. While these means may be of various characters, in the particular construction illustrated, there is provided a locking pin 18 provided with a flanged head 19. The arm 16 is provided with a central hub 20 recessed to receive the locking pin and a spring 21 surrounding the pin. The other end of this pin 18 drops in a recess 20' in a projection on the framing, when the arm 16 is rotated.

to advance the core, and holds the parts in locked position. This pin is operated to release the arm by the operation of the handle 17. To effect this, this handle is a two part handle, the lower part of which is stationary, being supported in a hub 22 carried on the lower part of the arm 16. The upper part of this handle 23 is pivoted on a pin 24 secured in the outer end of the hub and carries 10 a yoke 25 engaging the locking pin 18. By depressing the handle 23, the pin is moved to the right and the arm can then be swung. If desired, a stop 26 may be provided for stopping the arm.

15 In the best constructions, means are provided for adjusting the movement of the block. While these means may be somewhat varied, in the particular construction shown, the two parts of the block 3, 3' are held together so as to have a relative sliding engagement by a key 27. The block 3' is provided with a recess 28 which receives a projection 29 extending inwardly from an adjusting wheel 30. The projection 29 is provided with 20 an annular groove 31 in which seats a two part collar 32, this collar being secured to part 3 of the blocks by screws 30', the wheel 30 thus being secured to the block 3. The projection 29 is provided with a threaded 25 opening 33 which receives one end of a screw 34, the other end of the screw 34 being tapped into the block 3', this screw being provided with a collar 35. By turning the handwheel 30, the screw 34 will effect an adjusting movement of the block 3' relatively to the block 3, the block sliding in the recess 28. This adjustment is provided to effect a movement of one of the cones independent of the movement given the cone by the pinion 13 so that 30 the cone may be so positioned relatively to the roll as to enter the roll core the required distance. This construction is needed and is therefore shown as used with only one of the chucks.

45 The block 3 is held against rotation in any suitable manner so as to insure engagement of the rack and pinion, as by a set screw 36.

With the construction shown and described, it will be seen that a very simple and 50 efficient chuck for holding a web roll has been provided, one of few parts which is very quickly and easily manipulated, and one in which the parts are so arranged as to be automatically locked, it being necessary to 55 operate the locking means only when it is desired to release the chucks.

While the invention has been shown and described in its preferred form, it will be 60 understood that various changes may be made in the specific arrangement of the parts and that the invention is not to be restricted to the construction and arrangement shown and described.

65 What I claim is:

1. In a chuck mechanism for supporting a web roll, the combination with framing of inner and outer telescoping blocks having a sliding movement in the framing and non-rotatable with respect to each other, a core 70 engaging member carried by one of the blocks, a rack carried by the other of the blocks, a gear engaging the rack, an operating arm for operating the gear, and means for locking the arm in core engaging position. 75

2. In a chuck mechanism for supporting a web roll, the combination with framing, of a block having a sidewise movement in the framing, a cone-journal carried by the block for engagement with the core of the roll, an outer block telescoping with the first block and non-rotatable with respect thereto, a rack on the outer block, a gear for driving the rack, an operating arm for operating the gear, and means for effecting a movement of the first block with respect to the roll core for adjusting the position of the cone. 80

3. In a chuck mechanism for supporting a web roll, the combination with framing, of an outer block having a sidewise movement 90 in the framing, a rack carried by the block, a gear for operating the rack, an inner second block having a sidewise movement in the first block and carrying a cone-journal for engagement with the core of a roll, and means concentric with the inner block for effecting a movement of the inner block with respect to the roll core and independent of the gear for adjusting the sidewise position of the cone. 95

4. In a chuck mechanism for supporting a web roll, the combination with framing, of an outer block having a sidewise movement in the framing, a rack carried by the block, a gear for operating the rack, an inner second block having a sidewise movement in the first block and carrying a cone-journal for engagement with the core of a roll, a screw secured in the inner block, and means for operating the screw to effect an adjusting movement of said inner block independently of the outer block and relatively to the core of the roll. 100

5. In a chuck mechanism for supporting a web roll, the combination with framing of an outer block having a sliding movement in the framing, an inner block telescoping with the outer block and carrying a cone-journal for engagement with the core of a roll a rack on the outer block, a gear for operating the rack to effect a quick adjusting movement of the cone to and from the core, a screw concentrically engaging the inner block, and a hand wheel for operating the screw to give a fine adjusting movement of the inner block independently of the outer block and relatively to the roll. 115

6. In a chuck mechanism for supporting a web roll, the combination with framing, of a member having sliding movement in the 120

framing, a rack for effecting a sidewise movement of the member, an operating arm having a gear engaging the rack, a member mounted in telescopic relation with the first member and non-rotatable with respect thereto and having sliding engagement with the roll core, means for effecting a movement of the core engaging member with respect to the roll core and independent of the gear, and means for locking the operating arm in position.

In testimony whereof, I have hereunto set my hand.

HERMAN P. CLAUBERG.
